United States Patent

Des. 234,861
Patented Apr. 15, 1975

234,861

SLIDE POOL

Ascher Chase, Norfolk, Va., assignor to General Foam
Plastics Corp., Norfolk, Va.

Filed July 27, 1973, Ser. No. 383,084

Term of patent 14 years

Int. Cl. D21—01

U.S. Cl. D34—5 F

FIG. 1

FIG. 2

FIG. 3

FIG. 4

FIG. 5

FIG. 1 is a perspective view of a slide pool embodying my new design;

FIG. 2 is a plan view of the new slide pool;

FIG. 3 is a side elevational view of the new slide pool;

FIG. 4 is a front elevational view of the new slide pool; and

FIG. 5 is a rear elevational view of the new slide pool.

I claim:

The ornamental design for a slide pool, substantially as shown.
